INDICATOR BELT

Masao Yoshimura, Inglewood, Calif., assignor to The Mailbox, Inc., Los Angeles, Calif.

Filed Dec. 6, 1972, Ser. No. 312,597

Term of patent 14 years

Int. Cl. D2—07

U.S. Cl. D2—380

FIG. 1 is a front perspective view of an indicator belt showing my new design;

FIG. 2 is a rear perspective view thereof;

FIG. 3 is an enlarged fragmentary side perspective view of the buckle portion of the belt;

FIG. 4 is an enlarged fragmentary elevational view of the back of the belt; and

FIG. 5 is an enlarged fragmentary elevational view of the front of the belt.

I claim:

The ornamental design for an indicator belt, substantially as shown.
